UNITED STATES PATENT OFFICE.

SILAS M. FORD, OF ST. PAUL, MINNESOTA.

LATH-BOARD.

1,180,125.

Specification of Letters Patent. Patented Apr. 18, 1916.

Application filed August 9, 1915. Serial No. 44,509.

To all whom it may concern:

Be it known that I, SILAS M. FORD, a citizen of the United States, residing at St. Paul, in the county of Ramsey and State of Minnesota, have invented certain new and useful Improvements in Lath-Board, of which the following is a specification.

My invention relates to improvements in lath-board made of flexible sheeting corrugated to form lath projections and intermediate plaster receiving depressions, and designed to be fastened to the studding or beams of structures to form a foundation for plaster.

15 The object of the invention is to provide the board with improved reinforcing strips incorporated in the sheet to hold the corrugations to form and to prevent the plaster from slipping.

20 To these ends the invention consists in the construction, combination, and arrangement of parts hereinafter described and claimed.

In the accompanying drawings forming part of this specification, Figure 1 is a perspective view of the outer side of a fragment of lath-board embodying the invention; Fig. 2 is a perspective view of the underside of a fragment of the lath-board; Fig. 3 is a cross section on line $x-x$ of Fig. 1; Fig. 4 is a perspective view of the board shown secured upon a backing sheet and with reinforcing strips upon the outer side only; Fig. 5 is a perspective view of a fragment of the board shown with a modified form of corrugations; and Fig. 6 is an end view of the board shown in Fig. 5.

The lath-board of the present invention is made preferably of waterproofed paper, such as rope stock surfaced or impregnated with asphalt or the like. The sheet is bent or molded under pressure to form corrugations or alternate lath projections and depressions. In the form shown in Figs. 1, 2, and 3 of the drawings every other projection is of keyed lath shape, that is with its sides inclined downwardly and inwardly toward each other, such as the projections 2, while alternating with these projections are lath projections 3 having their sides inclined outwardly away from each other. Between the lath projections are depressions or recesses 4 located in the angles between the inwardly inclined sides of the projections 2 and the outwardly inclined sides of the adjacent projections 3. Beneath each keyed lath projection 2 is a triangular air space 5 con-

tracting toward the bottom, and beneath each projection 3 is an air space 6 spreading or widening toward the bottom.

If desired all of the lath projections and 60 depressions may be made of keyed lath shape form, as shown in Figs. 5 and 6, where 7 represents the stamped up lath projections and 8 the intermediate depressions adapted to receive and hold the plaster. As in the 65 forms shown in Figs. 1 and 3 the spaces beneath the lath projections serve as heat insulating and sound deadening spaces. To hold the corrugations to form, that is to prevent them from becoming flattened or 70 crushed in use, as well as to provide means for preventing the plaster from slipping I incorporate in the board reinforcement strips 9 and 10, preferably of sheet metal. These strips extend transversely across the 75 corrugations upon the outer and inner sides thereof, respectively, at spaced intervals and are bent to follow the corrugations of the sheet. The strips may be first laid on the sheets and then corrugated with the sheets 80 and in the same operation, or they may be first molded by an independent operation and then slipped endwise over the corrugations. It will be seen that these strips following closely the bends and folds of the 85 corrugations and fitting snugly against the surfaces of the board will effectually hold the corrugations to form. It is ordinarily sufficient to provide the reinforcing strips upon one side only of the board using pref- 90 erably the strips 9 upon the outer side of the board, rather than the strips 10 upon the underside of the board as the strips upon the outer side hold the corrugations better to form, and also afford locks to prevent the 95 plaster from slipping.

If desired the corrugated sheet may be placed upon a suitable backing sheet 11 and made to adhere to it by asphalt or other suitable binding means, as shown in Fig. 5, or be secured thereto by means of staples 12 as shown in Fig. 4. The reinforcing strips 9 and 10 extending transversely of the board and bent or corrugated to follow the corrugations thereof constitute an easily applied 105 and particularly effective means of holding the corrugations to form, and, when placed on the outer side of the board, serve to prevent the plaster from slipping.

I claim:

1. A lath-board comprising a sheet of flexible material corrugated to form inter-

- spaced lath projections, and intermediate depressions, and reinforcing strips extending across the sheet transversely of the corrugations and corrugated to conform to the 5 corrugations of the sheet, whereby to hold the corrugations of the sheet to form.
2. A lath-board comprising a sheet of flexible material corrugated to form interspaced lath projections and intermediate 10 depressions and reinforcing strips extending

across the sheet transversely of the corrugations on both outer and inner sides thereof and being themselves corrugated to conform to the corrugations of the sheet.

In testimony whereof I affix my signature 15 in presence of two witnesses.

SILAS M. FORD.
